APPARATUS FOR DRY COOLING COKE

Application filed March 14, 1929, Serial No. 347,077, and in Belgium February 2, 1929.

It has been previously proposed in apparatus for regenerating sensible heat from hot coke, to let this coke into the upper part of a shaft which may contain a certain number of 5 pieces of coke, thus yielding the heat during the progressive fall to an ascending current of non-oxidizing gases which transfer this heat to a generator of heat. According to the more or less friable nature of the coke 10 produced, this method of cooling of the coke by convection may offer the drawback that those portions of the coke layers which contain dust, offer a greater resistance to the passage of gases and under these conditions, 15 the cooling is effected in a very irregular manner. It happens that the coke which on its descending way down the shaft is surrounded by dust, is still very hot at its outlet at the lower part of the shaft, and that special measures become necessary for rendering its transport possible.

The object of the present invention is an apparatus which shall avoid these drawbacks.

According to the present invention, it has been found useful to maintain the method of cooling the coke by convection, by means of a continuous current of non-oxidizing gases; each cake of coke is, however, cooled 25 separately, means being provided for bringing each piece of coke into contact with a continuous current of gases, which traverses several times the coke spread in a sufficiently thin layer.

The coke is preferably spread on an inclined stepped surface with plates arranged in the manner of a shutter or Venturian blind, which forms the floor of several adjacent chambers provided with sidewalls and with 30 roofs made of refractory bricks. Each sidewall of these chambers may extend below the inclined surface, and it runs along spaces which serve to regulate the passage of gases through the spaces left between the said 35 shutter-like plates. Underneath the plates of each chamber, are placed two of these spaces, the lower space receiving the gaseous current below the shutter-like plates provided at the lower part of the inclined area, and the upper space collecting the gaseous

current which has traversed the layer of coke situated above the shutter-like plates provided at the upper part of the inclined area. Between the spaces of two adjacent chambers, each of the sidewalls is preferably 55 traversed by an oblique opening serving to connect through a channel the upper space of the chamber situated on one side of the sidewall, with the lower space of the chamber situated on the other side of the sidewall. 60 A circuit is thus established which makes it possible that alternately opposite directions are successively given to the gaseous current acting as a carrier for the heat to be regenerated from the coke. On leaving the upper 65 space of the last chamber, the gaseous current is sent into a dust-collecting receptacle and comes afterwards into contact with the heating surface of the steam generator, from which it is taken again by a fan which returns it to the lower space of the first chamber. 70

The accompanying drawing illustrates by way of example one mode of carrying the 75 invention into effect.

Fig. 1 is a cross-section along the axis G—H of Figures 3 and 4 of one of the chambers serving for cooling the coke;

Fig. 2 is a vertical section along the line A—B of Fig. 1.

Fig. 3 is an inclined section made along the line C—D of Fig. 1.

Fig. 4 is an inclined section taken along the line E—F of Fig. 1, and Fig. 5 an enlarged section of a detail.

The coke to be cooled is brought by a coke car 1 in front of the chambers 2 which serve for cooling, and have their lower doors closed. It is thrown there, and it spreads itself on the 90 stepped inclined grate 3 which has pivoted shutter-like plates 17 hinged or pivoted at 19. Underneath this inclined grate are provided for each chamber and between the downwardly extending side walls 18 two spaces 4 and 5, separated by suitable partitions, of which the space 4 is placed underneath the lower portion of the inclined grate, and the space 5 is placed below the upper part of the 95 grate. Obliquely directed channels 6 con- 100

nect the space 5 of one of the chambers to the space 4 of the next chamber. The roofs and side walls are preferably made of refractory brick. The upper door 10 of the chamber 2 being closed, a fan 7 sends through a pipe 8 a current of non-oxidizing gases such as for example nitrogen or inert products of combustion into the space 4 of the first chamber 2, where this current passes between the shutter-like plates 17 of the inclined grate 3, and sweeps over the surface of the coke pieces which are spread thereon, rising afterwards along the roof 14 of the chamber, and descending through the layer of coke and between the shutter-like plates which cover the space 5 of the same chamber. From the space 5 of the first chamber, the gaseous current passes through the obliquely directed channel 6 into the space 4 of the second chamber 2 and ascends again between the shutter-like plates and through the coke situated in this second chamber, to be directed afterwards between the roof 14 upon the coke which covers the shutter-like plates of the space 5 of the same chamber. When leaving the space 5 of the second chamber 2 the gas follows the obliquely directed channel 6 connecting this space 5 to the space 4 of the third chamber 2, and after having ascended between the shutter-like plates of this space and through the coke which covers them, it arrives into the lower part of the third chamber, where it is re-directed by the roof 14 of the chamber upon the coke covering the shutter-like plates of the space 5 of this chamber. From the space 5, the heated gas is directed into the dust collecting receptacle 11, and afterwards to the upper part of the heating surface of the boiler 12. At the lower part of the boiler, a conduit 13 brings the cooled gas to the fan 7. When the coke is cooled to the required temperature, it is sufficient to open the lower door 9 of the chamber 2 in order to make it slide on the members serving for its transport.

I claim:

An apparatus for the dry cooling of coke spread in a thin layer comprising a series of adjacent compartments, an inclined stepped grate with pivoted shutter-like plates forming the floors of said compartments, said compartments having sidewalls and roofs of refractory brick, each sidewall extending below the inclined stepped grate and providing a separate upper and lower space below each compartment, the side walls having channels connecting the upper space of one chamber with the lower space of the subsequent chamber, means for passing a continuous current of non-oxidizing gas through each compartment, first upwards through the lower space and the lower part of the layer of coke, then through the upper part of the layer of coke and through the upper space of the same

chamber, and then through channels in the sidewalls from the upper space of one compartment into the lower space of the adjacent compartment.
